UNITED STATES PATENT OFFICE.

FRANCIS HENRY PATON BEATSON, OF VANCOUVER, BRITISH COLUMBIA, CANADA.

ADDITIONAL-AIR DEVICE FOR INTERNAL-COMBUSTION ENGINES.

1,403,003.

Specification of Letters Patent. Patented Jan. 10, 1922.

Application filed July 15, 1920. Serial No. 396,383.

To all whom it may concern:

Be it known that I, FRANCIS HENRY PATON BEATSON, a subject of the King of Great Britain, and a resident of the city of Vancouver, in the Province of British Columbia, Canada, have invented certain new and useful Improvements in Additional-Air Devices for Internal-Combustion Engines, of which the following is a specification.

10 My invention relates to improvements in additional air devices for internal combustion engines, with more particular reference to automobile engines, and the object of my invention is to provide a device by the use of which additional air may be admitted to the engine on the closing movement only of the carbureter throttle, thus enabling the rich gas mixture required for power to be weakened when the engine is trottled and the 20 power not required so that a great economy in saving the fuel consumption is effected.

I attain this object by the construction illustrated in the accompanying drawings in which—

25 Fig. 1 is a vertical section of the device taken through the centre line.

Fig. 2 is a sectional plan view taken on the line 2—2 of Fig. 1.

Similar figures of reference indicate similar parts throughout the several views.

The device consists of a body 1, preferably cylindrical in form, which is screwed into or bolted to the induction pipe of the engine and which contains the ports 2 and 3, these ports being positioned opposite to one another and formed parallel, tapered or otherwise graduated so that the volume of air admitted will be correct at any position of the throttle. Within the body 1 and frictionally held in contact with it is an outer sleeve 4 in the outer wall of which are formed ports 5 and 6 the depth of which is less than the thickness of the sleeve wall as shown, the inner wall of the sleeve, that is, 45 the bottom wall of the ports 5 and 6, being perforated by two opposite series of ports 7 and 8, the combined area of each respective series being equal to the area of the ports 2 and 3 respectively of the body. This 50 outer sleeve is capable of a circumferential movement equal to the length of the body ports 2 and 3 and it is operated as herein-after described, by a pin 9 carried by an inner sleeve 10 rotatably mounted within the outer sleeve and provided with two opposite 55 series of ports 11 and 12 adapted to register

with the respective series of outer sleeve ports 7 and 8 when the device is full open. The pin 9 extends into a slot 13 in the outer sleeve the length of which slot is such as 60 will permit of a circumferential movement of the inner sleeve free of the outer sleeve equal to the width of the outer sleeve ports 7 and 8 and the inner sleeve is operated by means of a lever 14 connected to a central 65 spindle 15 with which it is provided. The lower end of the device is provided with a suitable cover 16 while its opposite end is threaded, as at 17, or flanged, as indicated by the dotted lines and numeral 18, in Fig. 70 1, to enable it to be readily secured in place.

The manner in which the device is used and its utility will be apparent and may be briefly described as follows: The threaded or flanged end is secured to the induction 75 pipe of the engine and the lever 14 connected to the carbureter throttle control so that, with the throttle open, the ports are in the position shown in Fig. 2, that is, ports 2—3 and 5—6 are open to the full extent but the 80 series of ports 7 and 8 are covered by the walls between the ports 11 and 12 respectively. On the closing movement of the throttle, the series of ports 7 and 8 are uncovered by the walls just mentioned, the 85 ports 11 and 12 being carried into registration with ports 7 and 8 by the circumferential movement of the inner sleeve so that when the lever 14 reaches the dotted position shown in Fig. 2, the ports 7 and 8 are 90 full open, admitting to the engine the full amount of air passed through the ports 2 and 3 in the body 1. The pin 9 then contacts with the wall of the slot 13 opposite to that shown in Fig. 2 so that further movement of the lever 14 moves both the outer and inner sleeve coincidently so that the body ports 2 and 3 will then be closed in unison with the throttle. Immediately the 95 throttle is opened, the pin 9 travels the full length of the slot in the reverse direction, closing ports 7 and 8 and shutting off the additional air admitted on the closing movement, so that at any position of the throttle on the opening movement the ports 7 and 8 100 are fully closed, but are fully opened on the reverse movement from which it will be seen that the ports open rapidly as the throttle closes, admitting the full volume of air as controlled by ports 2—3 and 5—6 and weakening the gas mixture so that while the engine continues to run light the minimum of 110

fuel is used, thus ensuring the greatest economy possible while at the same time maintaining the mixture at full strength when the throttle is opened, since the air ports of 5 the device are then closed so that there is no interference with the mixture as set for power. This may be better understood if it is explained that a gas charge in an internal combustion engine, such as an auto- 10 mobile engine, will fire though the proportions of the mixture are varied through a wide range although of course, the power delivered will also vary. Let it be assumed for the purpose of illustration that in an en- 15 gine running at full load the gas charge consists of 1 part of gasoline to 10 parts of air. When the throttle is closed under present conditions the consumption of fuel is, of course, reduced but the relative proportion 20 of gas to air remains constant, that is, the strength of the mixture is unaltered, whereas the engine would continue to run light on much weaker mixture, say, 1 of gasoline to 16 parts of air and that is the object of 25 the present invention, that is, to maintain the gas charge at its maximum strength when the engine is running at full load and to dilute and weaken it to the minimum strength on which the engine will continue 30 to run light when required.

From the foregoing it will be seen that I have devised a simple and convenient device by the use of which great economy is effected in the operation of internal combustion engines.

What I claim as my invention is:

1. A device of the character described comprising a chambered body member adapted to be secured to, and opening into 40 an internal combustion engine induction pipe and provided with ports which remain closed throughout opening movement of the engine throttle and the opening of which ports is coincident with commencement of 45 closing movement of the throttle, said ports remaining fully open throughout said closing movement of the throttle and means operative coincident with the closing movement of the throttle for opening said ports. 50 2. A device of the character described comprising a chambered body member adapted to be secured to and opening into an internal combustion engine induction pipe, said body being provided with controlled 55 ports which remain closed throughout opening movement of the throttle and open throughout closing movement of the throttle, the commencement of opening movement of such ports being coincident with the commencement of the closing movement of the 60 throttle, a pair of sleeves controlling said ports, and means operative coincident with the closing movement of the throttle for opening said ports, said means being adapt- 65 ed to move both of said sleeves.

3. A device of the class described comprising, a ported body member adapted to be secured into an internal combustion engine induction pipe, a sleeve within said body held in frictional contact therewith 70 ported in its outer periphery correspondingly to the body ports and having a plurality of inner ports extending from its outer ports through its inner periphery, said sleeve being provided with a slot, an inner 75 sleeve circumferentially movable in said outer sleeve having a plurality of ports of equal area to the outer sleeve inner ports, a pin carried by said inner sleeve extending into the slot of the outer one and capable of 80 free movement therein to permit carrying of said inner sleeve ports into registration with the outer sleeve ports, and means for moving the inner sleeve.

4. A device of the class described comprising, a ported body member adapted to be secured into an internal combustion engine induction pipe, a sleeve within said body held in frictional contact therewith 90 ported in its outer periphery correspondingly to the body ports and having a plurality of inner ports extending from its outer ports through its inner periphery, said sleeve being provided with a slot, an inner 95 sleeve circumferentially movable in said outer sleeve having a plurality of ports of equal area to the outer sleeve ports, said sleeve being closed on its lower end and provided with a depending stem and a pin extending into the outer sleeve slot, said pin 100 being capable of free movement therein to permit carrying of said inner sleeve ports into registration with the outer sleeve ports, and a lever secured to said depending stem for operating said inner sleeve.

5. A device of the character described comprising a hollow ported body, a pair of ported sleeves contained one within the other and concentrically assembled with said body, a connection between said sleeves permitting the same to have a limited independent movement enabling the ports of one sleeve to pass into and out of registration with the ports of the remaining sleeve, and actuating means connected to one of said 110 sleeves.

6. A device of the character described comprising a hollow ported body, a pair of ported sleeves contained one within the other and concentrically assembled with said body, a projection carried by one sleeve and operating in a slot formed in the other sleeve to limit independent movement of the two sleeves, and means for rotating one of said sleeves.

7. The combination with the throttle and the fuel induction pipe of an internal combustion engine, of an additional air intake device comprising a hollow ported body in communication with the interior of said in- 125 130

duction pipe, a pair of ported sleeves contained one within the other, and concentrically assembled with said body, said sleeves being rotatable relatively to one another and to the said body to effect opening and closing of the body ports, means for limiting independent movement of the two sleeves, and means for connecting one of said sleeves to the throttle or throttle actuating means, whereby said sleeves will be actuated concurrently with the throttle.

8. A device of the character described comprising a hollow ported body, a pair of

rotatable sleeves contained one within the other and concentrically assembled with said body, each of said sleeves having a portion thereof corresponding in size with the body port, provided with a plurality of small ports adapted at times to be arranged opposite the said body port, and means for actuating said sleeves including means for limiting independent movement of the sleeves with respect to one another.

Signed at Vancouver, B. C., Canada, this 6th day of July, 1920.

FRANCIS HENRY PATON BEATSON.
